CLAIM

I hereby claim the design for the head light, as illustrated in our FIGS. 1-7, as shown and described above.

DESCRIPTION

FIG. 1 is a top, front, right side perspective view of a head lamp showing the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.
